[57] CLAIM

[21] Appl. No.: 29/112,481

The ornamental design for a top assembly for a single-lens
reflex camera body, as shown and described.

[22] Filed: Oct. 19, 1999

DESCRIPTION

[30] Foreign Application Priority Data

Apr. 19, 1999 [JP] Japan 11-10272

FIG. 1 is a perspective view of the top, front and right side
of a top assembly for a single-lens reflex camera body
showing my new design;

[51] LOC (7) Cl. 16-05

FIG. 2 is a front elevational view thereof;

[52] U.S. Cl. D16/219; D16/217

FIG. 3 is a top plan view thereof;

[58] Field of Search D16/200, 201,

FIG. 4 is a left side elevational view thereof;

D16/204, 205, 208, 209, 216-218, 219;

FIG. 5 is a right side elevational view thereof;

396/354-359, 535-541

FIG. 6 is a rear elevational view thereof; and,
FIG. 7 is a bottom plan view of the only portion of the top
portion visible when the top portion is assembled on the
camera body in use.

[56] References Cited

The remainder of the camera body and the control elements
shown in broken lines do not constitute a part of the claimed
design.
